CONVERSION OF HIGH BOILING POINT
HYDROCARBON OILS INTO LOWER
BOILING POINT HYDROCARBON OILS

Robert E. Wilson, Chicago, Ill., assignor to Standard Oil Company, Whiting, Ind., a corporation of Indiana

Application October 18, 1926, Serial No. 142,316

37 Claims. (Cl. 196—48)

The present invention relates to improvements in processes for the conversion of higher boiling point hydrocarbon oils into lower boiling point hydrocarbon oils, particularly of the gasoline type, wherein the conversion is effected by heating under pressure, and will be fully understood from the following description, illustrated by the accompanying drawings, in which:

Fig. 1 is a diagrammatic view of apparatus suitable for carrying the invention into effect and showing insulation and also condenser box in section;

Fig. 2 is a vertical sectional view through an expansion and reaction chamber as employed in accordance with the present invention;

Fig. 3 is a horizontal sectional view on the line 3 of Fig. 2;

Fig. 4 is a horizontal sectional view through the expansion and reaction chamber on the line 4, of Fig. 2;

Fig. 5 is a vertical sectional view through the tower receiving the vapors and unvaporized liquid from the expansion and reaction chamber;

Fig. 6 is a transverse sectional view through the tower of Fig. 5, on line 6;

Fig. 7 is a transverse sectional view through the tower of Fig. 5 on the line 7;

Fig. 8 is a transverse sectional view through the tower of Fig. 5 on the line 8;

Fig. 9 is a vertical sectional view of a receiving chamber or drum which receives condensates selected from various points in the column of Fig. 5;

Fig. 10 is a vertical sectional view through a vapor fractionating and stripping column;

Fig. 11 is a sectional view illustrating diagrammatically a water separating device; and

Fig. 12 is a vertical sectional view illustrating diagrammatically a device for separating gas from condensate.

Referring more particularly to the drawings, the numeral 20 indicates a furnace setting in which is mounted a pipe coil 21 through which the oil to be converted is passed under suitable conditions of pressure and temperature, as hereinafter more fully set forth, to bring it to the desired conversion conditions. The furnace and pipe coils may be constructed in any suitable manner, excessive local heating being avoided, and are adapted to be employed at high temperatures and pressures. A suitable method of constructing and operating the pipe still and setting is shown in my co-pending application Serial No. 145,515, filed November 1, 1926.

55 Pipe coils 21 in the setting 20 receive the stock

fed them from pipe 22 through the inlet pipe 23, and after it is brought to the desired temperature conditions, and the latter has been maintained for a suitable length of time, the heated oil is discharged from the pipe still through the 5 outlet pipe 24. If desired, more or less of the cooler feed stock may be supplied from the pipe 22 through the valved pipe 25 to the heated oil in the outlet pipe 24 immediately upon its discharge from the pipe still. The heated oil then 10 passes through a pressure reducing valve 26 and enters one or more valved nozzles 27, or nozzle valves as in my co-pending application Serial No. 112,024, filed May 27, 1926, by which it is introduced into the enlarged chamber or still 28, preferably tangentially in the lower portion thereof. This chamber is suitably constructed of heavy walled material to stand high pressures, although the pressures prevailing therein are not ordinarily as high as those maintained in the pipe 20 coils 21, and is preferably lagged. The enlarged chamber 28 is ordinarily unheated, the temperature attained by the oil in the coils 21 being such that a conversion temperature at which a rapid rate of conversion is attained, is maintained in the chamber 28. The nozzles 27 by means of which the heated oil is introduced into the chamber 28 are preferably tangentially disposed, and the agitation produced by the tangential introduction of the heated oil in the lower 15 portion of the chamber aids in minimizing any settling of tarry or coke sediment in the chamber 28. An approximately constant level of liquid is maintained in the chamber 28, a level indicator 29 operated by float 30 being provided for its 20 observation. Vapors separating from the liquid in the chamber 28 pass out through the vapor line 31 and enter, preferably tangentially, the lower portion of a lagged column 32, shown in sectional view in Figs. 5 to 8 inclusive. The un- 25 vaporized liquid or residue from the chamber 28 is drawn out substantially continuously through a pipe 33 protected by a baffle 34, (see Fig. 2) and enters the tower 32, likewise tangentially, at a point somewhat higher than the point of entrance of the vapors through line 31. Between the point of entrance of the vapor line 31 and that of the unvaporized liquid line or tar line 33 in the column 32 there are provided a number of 30 suitable fractionating plates 35, adapted to tolerate considerable coke without clogging, suitably of doughnut and disk type.

At an intermediate point in the column 32, above the point of entrance of the line 33 for unvaporized liquid, there is provided a cut-off 35

or trap-out plate 36 provided with a central cylindrical conduit or pipe 37 which permits free passage of vapors upwardly from the lower portion of the column 32. Through this cylindrical vapor pipe 37 the vapors enter a compartment of the tower separated from the upper portion of the tower by a partition 38. A pipe coil 39 is provided in the column around the vapor line 37, and vapors rising through the latter pass downwardly through the annular space surrounding it, passing around the pipe coils 39. Undecondensed vapors enter the external vapor pipes 40 by which they are led back into the column 32 at a point just above the partition 38. The vapors then rise through a plurality of fractionating plates 41, of which the lowermost is indicated as 41^a. Reflux condensate formed in this part of the tower flows downwardly to the lowermost plate 41^a. This plate, in the form illustrated, is provided with overflow pipes 42, which discharge into the small collecting chambers 43 connected by pipe 44. From one of these chambers 43, the condensate may be withdrawn through the line 45.

Condensate formed in the compartment between the plate 36 of the column and the partition 38 collects in the annular chamber surrounding the vapor pipe 37 and is withdrawn through the overflow pipe 46 and conduit 47. Below the plate 36 and above the point of entrance of the line 33 there are provided a number of fractionating plates 48, suitably of the bubble-cap type. Between two of these plates, means such as the conduit 49 are provided for the supply of a suitable oil to the column, as hereinafter more fully described. This oil may be, for example, a reduced crude oil.

In order to aid condensation and reflux formation in the upper part of the column 32, a suitable hydrocarbon oil, for example, of the kerosene range of boiling points, may be introduced above the plates 41, for example, through the conduit 50. Vapors undecondensed in the upper portion of the column 32 pass out through the vapor line 51. The column 32 is preferably operated at slightly above atmospheric pressure or at any suitable pressure below the pressure prevailing in the chamber 28, and lines 31 and 33 leading from the latter are suitably provided with suitable pressure reducing valves 52 and 53 respectively.

The oil removed from the column 32 through the line 45 enters the upper compartment of a two-compartment drum 54. The compartments are formed in this chamber by a partition 55 provided at its lowest point with an outlet pipe 56 leading to the conduit 57. Both the upper and the lower compartments of the chamber 54 are provided with level indicators 58 operated by floats 59. Liquid oil withdrawn from the column 32 through the line 47 enters the lower compartment of the drum 54, which is provided with a valved outlet pipe 60 at an intermediate point, this pipe connecting with the conduit 57.

The lower compartment of the drum 54 is likewise provided with a second valved discharge pipe 61 leaving near the bottom of the compartment. The conduits 57 and 61 are connected by a valved connection 62. A valve 63 is provided in the line 57 before this connection 62 is reached. From the point at which the connection 62 joins the line 61, a valved line 64 leads to a pump 65. From the point where the connection 62 joins the line 57, a valved suction line 66 leads to the pump 67. The pumps 65 and 67 discharge through

valved lines 68 and 69 respectively into the line 22 leading to the pipe still 21. Each of the pumps is likewise provided with a valved discharge connection 70 so that, if desired, the oil discharged by either pump may be forced to storage. By the connections just described, the pumps 65 and 67 can be made to handle separately the oil from the lower and upper compartments respectively of the drum 54; or either pump can be made to handle the combined oil from both compartments of the drum 54 or any desired proportions thereof. Pumps 65 and 67 are positioned below drum 54.

The vapors pass out of the column 32 through the vapor line 51, to column 71, illustrated in section in Fig. 10. The unvaporized liquid or tar from the bottom of the column 32 is discharged through the line 72 and passes through the heat exchanger 73, in which there is a heat exchange between the tar and oil supplied through pipe 125, as hereinafter set forth. The tar is then discharged from the heat exchanger through the pipe 76 to a suitable tar cooler 77, from which it passes out through line 78 to a tar pump 79, which discharges from the system through the line 80.

As hereinbefore stated, the vapors from the column 32 enter the fractional condensing column 71 at an intermediate point. Above the point of entrance of these vapors, there are provided a number of suitable fractionating plates, for example bubble plates 81 and below the point of entrance of the vapors, there are likewise provided a plurality of plates, suitably bubble plates 82. Any suitable means for supplying a cooling agent in the upper part of the column may be provided; for example, a cooling oil of the character hereinafter set forth may be supplied in the upper portion of the column through the pipe 83. Condensate formed in the column descends to the lower portion thereof and preferably a body of such condensate is maintained therein, suitable means, such as the float operated indicator 84 being provided for observing its level. If desired, steam may be supplied in the lower portion of the column 71, preferably below the surface of the condensate collected therein, for example, through the steam line 85 terminating in the perforated coil 86 in the lower portion of the column. The stripped condensate from the column is discharged through the valved line 87 and flows into a receiver 88, from which it is discharged by means of a pump 89. The discharge line 90 of the pump 89 is provided with a valved connection 91 leading to storage and with a second valved connection 92 connecting with the line 50 leading into the upper portion of the column 32, as already set forth. It is obvious that by means of these connections, controlled proportions of the condensate collected in the receiver 88 may be returned to the upper portion of the column 32 and employed as a cooling medium therein.

Undecondensed vapors passing out of the column 71 through the vapor line 93 enter the condenser 94 and the condensate and cooled gas pass therefrom through line 95 to a separator 96 of any suitable construction. A form of construction which may be employed for this separator is illustrated diagrammatically in section in Fig. 12. The condensate and gas enter through the line 95 in the lower portion of the separator 96, and above the point of entrance a plurality of suitable plates, such as the bubble plates 97 are provided. Within the separator 96 separation of liquid and

gas takes place, entrained liquid being separated from the gas by the action of the plates 97, aided by cold water or other suitable liquid supplied in the upper portion of the separator above the 5 plates 97 through the valve-controlled line 98. The separated gas passes out through the line 99 provided with a control valve 100. The condensate, together with the water added pass out from the bottom of the separator 96 through the line 101, which extends to the bottom of a trap 102, likewise illustrated diagrammatically in section in Fig. 12. The condensate and water pass out of the trap through the line 103 into a separator 104, illustrated diagrammatically in section 10 in Fig. 11. As shown in Fig. 11 the pipe 103 enters the separator 104, bending downwardly and opening at an intermediate point therein. Water separates from the condensate in the separator 104, and is withdrawn through the outlet pipe 105 which extends downwardly within the separator to the lower portion thereof. The separated light oil condensate overflows through the line 106 to the look box 107, from which discharge line 108 leads to the receiver 109. The 15 separator 104, look box 107 and receiver 109 are provided with gas vents 110, 111 and 112 respectively, which connect with a manifold 113 leading into a vent pipe 114 from the line 103 to an intermediate point in the gas separator 96, preferably below the uppermost plate 97.

The light condensate in the receiver 109 passes out through the line 115 to the pump 116, the discharge line 117 from which is provided a valve connection 118 leading to storage. A second 20 valve connection 119 is provided from the discharge line 117 and leading into the pipe 83 by which this condensate may be supplied to the upper portion of the column 71, as already described.

Oil is supplied for use in the system through the line 120 leading to the pump 121, by which it is forced through line 122, entering the coils 39, in which it is pre-heated by the vapors in the column. The oil leaving the coils 39 passes out 25 through the pipe 123 to a vapor separator 124. From the vapor separator 124, a liquid discharge line 125 leads to an end compartment of the exchanger 73. The oil passes through tubes in the exchanger and leaves from the opposite end 30 through the pipe 49 by which it is introduced into the tower 32 at an intermediate point below the partition 36.

In order that the invention may be fully understood, it will be described in connection with the treatment of a mid-continent oil, for example, a mid-continent crude or crude residuum. The crude oil from storage is supplied by line 120 to pump 121, by which it is forced through line 122 into and through the coils 39, in which it is heated to a temperature which is substantially below that at which appreciable cracking takes place (say, 350 to 450° F.) by the vapors from the lower portion of the tower 32, the nature of said vapors being more fully hereinafter pointed out. The 40 partially heated oil passes out of the coils 39 through the pipe 123 into the vapor separator 124. At the temperature of exit from the coil 39, a substantial amount of vaporization takes place. Vapors formed are released in separator 124 and pass out through line 125^a into one of the vapor lines 40 leading into the upper part of column 32. The liquid or oil from which the lighter vapors have been released passes out of the separator 124 through the line 125 and enters the heat exchanger 73, passing through the tubes 45

therein, the external surfaces of these being contacted with the residual oil from the base of the tower 32. There is some further heating of the oil in its passage through the tubes of the heat exchanger, and it makes its exit therefrom at a 5 temperature of 450 to 500° F. or thereabout.

The heated reduced crude oil then passes through the line 49 into the lower compartment of the tower 32 above at least some of the circulating or bubble plates 48 therein. The lower 10 compartment of the tower also receives converted oil products at a high temperature, as hereinafter more fully set forth, so that a substantial portion of the crude oil introduced through the line 49 is vaporized by the heat of the converted oil products; i. e., the products derived from the conversion system. The vapors from this oil, together with vapors from the converted products also supplied to the lower compartment of the tower, pass upwardly through the conduit 37 in 15 the partition 36, the temperature of these vapors being suitably in the neighborhood of 600 to 700° F. and preferably about 650° F. These vapors, after leaving the conduit 37, pass downwardly through the annular space surrounding it, and in doing 20 so contact with the outer surfaces of the coils 39, through which, as hereinbefore set forth, the crude oil is caused to pass. In the preferred form of construction, as illustrated, the vapors travel in countercurrent to the general direction of 25 movement of the crude oil passing through the coils 39. The vapors then pass out through the vapor lines 40 to the upper portion of the tower. The operation of the tower will be more fully described hereinafter. The condensate from the 30 vapors formed by the cooling action of the oil passing through the coils 39 collects in the tower on the partition 36 and is drawn off through the line 41 to the lower compartment of drum 54 in which a body thereof is maintained, its level 35 being indicated by the indicator 58 controlled by float 59. A lighter reflux condensate is drawn off from the tower 32 through the line 45 and this flows into the upper compartment of the drum 54, in which a body of this lighter condensate stock 40 is maintained, its level being observed by means of the float indicator 58. The stock may be drawn off from the lower compartment of the container 54 through the pipe 61 or through the pipes 60 and 57. The lighter reflux condensate 45 stock collected in the upper compartment of the drum 54 may be drawn off through the pipes 56 and 57. The stocks collected in the compartments of drum 54 are each substantially at its boiling point and either stock may consequently 50 be handled at a maximum temperature and with a minimum loss of heat. By suitable connections, which have already been fully described, the oil from either compartment of the drum 54, or mixtures thereof, in any desired proportions 55 may be picked up by either or both of the pumps 65 and 67 and forced through the lines 68 and 69 respectively into the feed line 22 by which the oil to be converted is fed to the conversion furnace 20. These pumps put the oil under high 60 pressure, suitably a pressure of 900 to 1200 lbs., although if desired pressures from 500 lbs. upwards may be employed.

The feed stock, under pressure, is forced through the pipe coils 21 in the furnace 20 in 65 which it is brought to conversion temperature and preferably under such conditions that a very substantial conversion is effected (say from 10 to 25% and preferably above 13%) into desired low boiling point products in the gasoline boiling 70

- point range at the time the oil emerges from the coil through the outlet pipe 24. The velocity of flow is maintained at such a rate that substantially no deposition of coke takes place within 5 the pipe still 21. The oil is discharged therefrom at a suitable temperature in excess of 780° F., and preferably at a temperature of 850 to 950° F., the pressure at the outlet of the coil being suitably 900 to 1100 lbs.
- 10 The heated oil then passes through pressure release valve 26 and through the tangential discharge nozzles 27 provided with pressure release valves and enters near the bottom of the enlarged chamber 28 which is preferably insulated 15 so that a conversion temperature is maintained therein. The pressure maintained in the chamber 28 is also very high, (above 100 lbs. per square inch), although preferably not above 750 lbs. per square inch. For example, a pressure of 250 to 20 750 lbs. per square inch or preferably about 500 lbs. may be maintained therein. The temperature of the material in the interior of the chamber 28 is maintained at from 740 to 860° F., for example, about 800° F. In order to aid in 25 securing the desired temperature in the chamber 28, feed stock may be diverted from the main feed line 21 through the valved line 25 to the outlet pipe 24 from the pipe still 21. A controlled amount of the cooler feed stock may be supplied 30 through this line to the heated feed stock emerging from the coil. In this way any desired control of the temperature within the chamber 28 below the temperature at the outlet of the pipe coil may be secured.
- 35 In the still 26 a separation of vapors from unvaporized oil takes place. The unvaporized oil, drawn off from a point near the surface of the liquid body in the still through the line 33, enters the column 32 after passing through the discharge valve 53 by which it is reduced to a substantially lower pressure, preferably only slightly above atmospheric; for example, 2 to 5 lbs. This unvaporized oil enters the lower compartment of the column 32 at an intermediate point below 40 the fractionating plates 48 and above the fractionating plates 35. As a result of the reduction of pressure, there is a substantial cooling of the material discharged from the outlet pipe 33, and there is also a substantial vaporization of the oil. Under the conditions herein described, the 45 products will be discharged from the line 33 at a temperature of 700 to 750° F. The vapors from the still 28 pass out through the line 31 and enter the column 32 in the lower portion thereof, below 50 the plates 35 and below the point of entrance of the line 33 carrying products unvaporized in the still 28. A pressure release valve 52 is provided in the vapor line 31, and is so controlled that the vapors from the still 28 enter the column 32 55 at a pressure equal to or only slightly more than the pressure at which the products passing through the line 33 enter the column 32. In general the vapors enter the column 32 at a somewhat higher temperature than the products issuing from the line 33. Both the lines 31 and 60 33 may be caused to enter the column 32 tangentially, as indicated clearly in section in Fig. 8.
- The vapors released from the products unvaporized in the still 28 and discharged through 65 the line 33 rise in the column 32 and pass through the bubble plates 48 in the customary manner. The unvaporized liquid or tar descends the column and, by the action of the fractionating plates 35 is brought into intimate contact with 70 the ascending vapors brought in through the line 75
31. These vapors strip the lighter constituents of the liquid, and in this action they are assisted by the fact that they are at a somewhat higher temperature than the liquid itself. At the same time, if desired, steam may be introduced into 5 the column through the line 127. The vapors derived from the converted products rise through the lower portion of the column and pass upwardly through the conduit 37. As has already been pointed out, crude or reduced crude oil, or 10 other feed oil, which has been preheated by vapors in the tower 32, is introduced into the lower portion of the column above the lower of the fractionating plates 48 by means of the line 49. A substantial portion of this oil is vaporized by 15 the heat of the products derived from the still 28 and the pipe still 21, and these vapors pass upwardly through the conduit 37 with the vapors from the converted products. The combined vapors then pass downwardly through the annular chamber surrounding the conduit 37 and containing the coil 39 through which the crude oil entering the system is passed for preheating. There is a substantial cooling of the vapors by 20 the cooler oil with the result that a condensate is formed which collects in the annular chamber above the partition 36. The approximate temperature at this point may be, under normal conditions of operation, about 500 to 600° F. The temperature is preferably maintained sufficient- 25 30 ly high to cause all of the gasoline fractions and most or all of the kerosene fractions remain in vapor state. The condensate formed is drawn off through the overflow pipe 46 and the line 47 to the drum 54 to form a part of the feed stock 35 for the pipe still, as hereinbefore described, and consists of vaporized and subsequently condensed portions from both the crude oil and the conversion products from the system. The vapors pass through the vapor pipes 40 to the upper portion 40 of the column above the partition 38 and rise through the bubble plates 41^a and 41. Suitable cooling means may be employed in this portion of the tower; for example, a condensate fraction of the nature of kerosene may be pumped into 45 the upper portion of the column through the line 50. Substantially all of the oil so introduced is vaporized and passes out through the vapor line 51 with the uncondensed vapors. The condensed products reflux to the lower plate, from which 50 the overflow pipes 42 lead to the chambers 43 which are interconnected by pipe 44 and from which reflux condensate is drawn off through the line 45 to the upper compartment of the drum 54. This reflux condensate which contains both un- 55 converted products directly derived from crude oil or reduced crude oil introduced into the lower portion of the tower 32 and converted products derived from the pressure heating system is of lighter character than the condensate drawn off 60 through the line 47. The temperature conditions within the upper portion of the column are preferably so maintained that substantially no products of the gasoline range boiling point are retained within the condensate formed and 65 drawn off through the pipe 45, these being largely in the gas oil and/or kerosene range of boiling points. The products of the gasoline together with more or less in the kerosene range of the boiling points pass off through the vapor conduit 70 51 and enter the fractionating and stripping column 71 at an intermediate point. The vapors rise through the fractionating plates 81 above their point of admission in the column 71. Suitable cooling means should be provided in the 75

upper portion of the column. A suitable cooling oil, for example, of the nature of the final condensate, may be supplied above the uppermost plate through the line 83. Reflux formed in the 5 column descends to the lower portion thereof, passing downwardly through the stripping plates 82 and collecting in the bottom of the column, the level of the collected condensate being indicated by the level indicator 84. A suitable inert gas or 10 other stripping medium, such as steam may be supplied in the lower portion of the column, for example, through the line 85 and the perforated distributing pipe 86. The steam and vapors pass upwardly through the column and aid in stripping 15 the reflux of its lighter ends. As a result of the action of the column 71, which may be suitably controlled, vapors of the desired low boiling end products such as those of the gasoline boiling point range, pass out through the 20 vapor line 93, together with such steam as may be used in the column. The heavier boiling point products, for example, of the kerosene boiling point range, or the heavier portion of the gasoline form the reflux condensate collected in the 25 bottom of the column and passes out at a controlled rate of discharge through the line 87 to the receiver 88. From the receiver, it may be picked up by pump 89 and discharged through the line 90, which is provided with two valve connections; one, designated by the numeral 91, leading 30 to storage and the other, designated 92, leading to the line 50 so that any predetermined quantity of these hydrocarbons may be supplied to the upper portion of the uppermost compartment of the column 32 in order to produce the desired cooling action therein, as hereinbefore described. The vapors of the low boiling point products, together with steam pass out of the column 71 through the line 93 and enter the condenser 94, passing through the coil therein, the 35 condensed and cooled products discharging through the line 95 into the separator 96, shown in Fig. 12. This separator contains plates, suitably of the bubble cap type. The condensed and cooled products enter in the lower portion of the drum or separator 96. The condensed portions are separated and discharged through the line 101. Gas passes out, ascending through the plate 40 97 and preferably washed by a hydrocarbon fraction, suitably of the gasoline range of boiling points, supplied through the line 98. The washed gases then pass out through the line 99, preferably to a suitable absorption system for removing therefrom their gasoline constituents. 45

The separated condensate discharged through the line 101 passes through the trap 102 and out through the line 103 to the water separating device 104, shown in section in Fig. 11. Separation of water takes place in this device, and the 50 separated water is discharged from the lower portion of the tank through the line 105, while the light oil or gasoline passes out through the line 106 and the lock box 107 to the receiving chamber 109. The line 103, the separator 104, the lock box 107 and the receiver 109 are provided with vents which discharge through the line 114 into the gas separating drum 96, preferably below the uppermost plate therein. 55

The gasoline condensate collected in the receiver 109 is picked up through the line 115 by the pump 116 and discharged through the line 117. The latter is provided with a valved connection 118 leading to storage and with a second valved connection 119 leading to the line 83 by which controlled quantities of the gasoline 60

distillate may be supplied to the upper portion of the column 71 as a cooling medium therein.

The operation of the process and apparatus of this invention has been described in connection with the utilization of a crude or reduced crude oil as the initial material. The material fed to the pipe still 21 is preferably a distillate or overhead stock, and in the embodiment above set forth, is a mixed stock, partly virgin and partly cycle; that is, part of it is derived from the distillation of a crude oil while the remainder is derived from an oil which has already been through the conversion system. The heavier condensate fractions drawn off from the tower 32 through the line 47 may be employed alone; 10 or the lighter condensate fractions of the nature of burning oil, drawn off through the line 45 may be employed, or mixtures of the two may be used as desired. If, however, it is regarded as preferable not to employ a crude or reduced crude oil 15 in the process nor to utilize the superfluous heat of the products of conversion to effect its distillation, a suitable overhead or distillate oil such as gas oil, burning oil, heavy naphtha or the like may be preheated in the same manner as the 20 crude oil in the process as hereinbefore set forth and then fed into the column 32 above the plate 36 to be drawn off together with reflux condensate through the line 47 as feed stock. 25

I claim:

1. The method of converting hydrocarbon oils into lighter hydrocarbon oils of the gasoline range boiling points which comprises passing the oil to be converted through a confined passageway while heating the latter to bring the oil to 35 a conversion temperature in excess of 800° F. and maintaining thereupon a pressure in excess of 750 lbs. per square inch, discharging the oil into an enlarged chamber maintained under a pressure materially below that prevailing in the 40 confined passage and in excess of 100 lbs. per square inch while maintaining in said chamber a conversion temperature not above that of the heated oil discharged from the coil, separately removing vapors and unvaporized oil from said 45 chamber, separately reducing the pressure upon the removed vapors and unvaporized products whereby the latter are reduced to a temperature below that of the vapors, discharging the said products unvaporized in said chamber into an 50 other chamber maintained under a materially reduced pressure passed downwardly therethrough and discharging the products vaporized in said enlarged chamber into said reduced pressure chamber below the point of admission of 55 said unvaporized products to pass upwardly therethrough countercurrent to the said unvaporized products.

2. The method of converting hydrocarbon oils into lighter hydrocarbon oils of the gasoline 60 range of boiling points which comprises passing the oil to be converted in a continuous stream through a confined passageway while heating the latter to bring the oil to a conversion temperature in excess of 800° F., maintaining thereupon a 65 pressure in excess of 750 lbs. per square inch discharging the oil into an enlarged chamber at a pressure materially below that prevailing in the confined passage and in excess of 100 lbs. per square inch while maintaining in said chamber 70 a conversion temperature not above that of the heated oil discharged from the coil, separately removing vapors and unvaporized oil from said chamber, separately discharging the conversion products into another chamber maintained 75

under a materially reduced pressure whereby the unvaporized products are cooled to a temperature below that of the vaporized products, contacting the removed vapors with the unvaporized portion of the conversion products in countercurrent flow within said reduced pressure chamber and separating vapors and unvaporized products within said chamber.

3. The method of converting hydrocarbon oils into lighter oils of the gasoline range of boiling points which comprises passing the oil to be converted in a continuous stream through a confined passageway while heating the latter to bring the oil to a conversion temperature in excess of 800° F., maintaining thereupon a pressure in excess of 750 lbs. per square inch, discharging the oil into an enlarged chamber at a pressure materially below that prevailing in the confined passage and in excess of 60 lbs. per square inch while maintaining in said chamber a conversion temperature not above that of the heated oil discharged from the coil, separately removing vapors and unvaporized oil from said chamber, separately discharging the conversion products into another chamber maintained under a materially reduced pressure whereby the unvaporized products are cooled to a temperature below that of the vaporized products, contacting the removed vapors with the unvaporized portion of the conversion products in countercurrent flow within the reduced pressure chamber, separating vapors and unvaporized products within said chamber, subjecting the vapors in said chamber to cooling, thereby partially condensing the same, withdrawing the resulting condensate, and forcing it into the continuous stream of oil flowing through the heated confined passageway.

4. The method of converting hydrocarbon oils into lighter hydrocarbon oils of the gasoline range of boiling points which comprises passing the oil to be converted in a continuous stream through a confined passageway while heating the latter to bring the oil to a conversion temperature in excess of 800° F., maintaining thereupon a pressure in excess of 750 lbs. per square inch, discharging the oil into an enlarged chamber at a pressure materially below that prevailing in the confined passage and in excess of 100 lbs. per square inch while maintaining in said chamber a conversion temperature not above that of the heated oil discharged from the coil, separately removing vapors and unvaporized oil from said chamber, separately discharging the conversion products into another chamber maintained under a materially reduced pressure, whereby the unvaporized products are cooled to a temperature below that of the vaporized products, contacting the removed vapors with the unvaporized portion of the conversion products in countercurrent flow within the reduced pressure chamber, separating vapors and unvaporized oil within said chamber, subjecting the separated vapors within the reduced pressure chamber to the cooling action of fresh oil to be converted, thereby forming reflux condensate and preheating the oil to be converted, and forcing the preheated fresh oil and reflux condensate into the heated confined passageway.

5. An apparatus for effecting conversion of high boiling hydrocarbon oils into lower boiling hydrocarbon oils such as gasoline, means for maintaining a body of oil at conversion temperature and pressure, means for separately withdrawing vapors and unvaporized products from said body of oil, a baffled chamber, means for introducing

the withdrawn unvaporized products into the baffled chamber at an intermediate point therein and at reduced pressure, means for introducing the withdrawn vapors from the body of oil at reduced pressure into the baffled chamber below the point of entrance of the unvaporized products, whereby such vapors pass upwardly in countercurrent to the unvaporized oil products, means for introducing crude oil into the baffled chamber at an intermediate point above and 10 close to the point of admission of the unvaporized products from the body of oil undergoing conversion, whereby the rising vapors in the baffled chamber vaporize portions of said crude oil, means for subjecting the mingled vapors 15 in the upper portion of the baffled chamber to cooling action, thereby forming reflux condensate, means for withdrawing said reflux condensate, and means for heating it to conversion temperature under pressure higher than that of the body 20 of oil maintained at conversion temperature and pressure and discharging it into the latter with reduction of pressure.

6. The method of converting hydrocarbon oils into lighter hydrocarbon oils of the gasoline range boiling points which comprises passing oil to be converted in a continuous stream through a confined passageway while heating the latter to bring the oil to a conversion temperature and maintaining thereon superatmospheric pressure 30 sufficient to maintain a substantial portion of the oil in the so-called liquid phase, introducing a controlled proportion of cooler oil into the stream of heated oil leaving the confined passageway, reducing the pressure on the mixed oil products 35 and discharging them into an enlarged chamber at a materially reduced superatmospheric pressure while maintaining a conversion temperature therein, separately removing vapors and unvaporized oil from said chamber, and separately 40 discharging them into another chamber maintained under a materially lower pressure in which the vapors enter at a point below that of entry of the unvaporized oil, the latter being cooled to a lower temperature than said vapors by the 45 reduction in pressure and contacting the separately removed vapors with the unvaporized portion of the conversion products by countercurrent flow in said last mentioned chamber.

7. The method of converting hydrocarbon oils into lighter hydrocarbon oils of the gasoline range of boiling points which comprises passing oil to be converted in a continuous stream through a confined passageway while heating the latter to bring the oil to a conversion temperature and maintaining thereon a high superatmospheric pressure sufficient to maintain a substantial portion of the oil in the so-called liquid phase, reducing the pressure on the heated oil and discharging it into an enlarged chamber maintained 60 under a materially lower superatmospheric pressure whereby a desired vaporization is secured in said enlarged chamber, and maintaining conversion temperature therein, separately removing 65 vapors and unvaporized oil from said chamber, separately reducing the pressure upon said vapors and unvaporized oil whereby the latter is cooled to a lower temperature than are the vapors, and discharging the said vapors and unvaporized oil at materially reduced pressure into another chamber at separated points, the vapors below the unvaporized oil and causing them to pass in countercurrent flow through said chamber to effect a further heating of unvaporized oil 75

- products and removal of light products therefrom.
8. The method of effecting the conversion of hydrocarbon oils into lower boiling hydrocarbon oils which comprises heating the oil to be converted under superatmospheric pressure to a conversion temperature and separating it into a vaporized portion and an unvaporized portion while under superatmospheric pressure, separately reducing the pressure upon said vaporized and unvaporized portions, whereby the latter are reduced to a temperature below that of the vapors, admixing the resulting unvaporized portions with fresh oil and contacting them with said vaporized portions in countercurrent flow, whereby the mixture is heated and constituents thereof vaporized, separately withdrawing the remaining unvaporized residues, subjecting the resulting vapors to partial condensation and passing selected portions of the resulting condensate to the conversion stage as the charging stock therefor.
9. The method of converting hydrocarbon oils into lower boiling hydrocarbon oils which comprises passing the oil to be converted in a continuous stream through a confined passageway while heating the latter to bring the oil to a conversion temperature and maintaining thereon superatmospheric pressure, reducing the pressure on the heated oil and discharging it into an enlarged chamber maintained under a materially reduced superatmospheric pressure to secure a desired vaporization therein while maintaining a conversion temperature in said chamber, separately removing vapors and unvaporized oil from said chamber and materially reducing the pressure thereon whereby the unvaporized oil is brought to a lower temperature than the vapors, discharging the unvaporized oil into another chamber, admitting fresh oil to the said other chamber at a point close to the admission point of the said unvaporized oil and admixing the latter therewith, introducing said vapors separately at a lower point in said chamber and causing them to pass upwardly through said chamber countercurrent to the mixture of vaporized oil and fresh oil constituents whereby said mixture is heated and lower boiling constituents thereof removed as vapors.
10. The method of converting hydrocarbon oils into lower boiling hydrocarbon oils which comprises passing the oil to be converted in a continuous stream through a confined passageway while heating the latter to bring the oil to a conversion temperature and maintaining thereon superatmospheric pressure, reducing the pressure on the heated oil and discharging it into an enlarged chamber maintained under a materially reduced superatmospheric pressure to secure a desired vaporization therein while maintaining a conversion temperature in said chamber, separately removing vapors and unvaporized oil from said chamber and materially reducing the pressure thereon whereby the unvaporized oil is brought to a lower temperature than the vapors, discharging the unvaporized oil into another chamber and admixing it therein with fresh oil constituents, introducing said vapors separately at a lower point in said chamber and causing them to pass upwardly through said chamber countercurrent to the mixture of vaporized oil and fresh oil constituents whereby said mixture is heated and lower boiling constituents thereof removed as vapors, separately withdrawing the remaining unvaporized residues, subjecting the said removed vapors to a partial condensation

operation and passing at least a portion of the resulting condensate to the said conversion stage as the charging stock therefor.

11. The method of converting relatively high boiling hydrocarbon oils into lower boiling products which comprises flowing a stream of condensate stock formed in the operation through a confined passageway while heating the latter to bring the oil stream to a conversion temperature in excess of 800° F. and maintaining thereupon a pressure in excess of 750 lbs. per sq. inch, discharging the stream into an enlarged chamber maintained under a pressure materially below that prevailing in the confined passage and in excess of 100 lbs. per sq. inch, maintaining in said chamber a conversion temperature not above that of the heated oil discharged from said passageway, separately removing vapors and unvaporized oil from said chamber and discharging said products into another chamber maintained under a materially reduced pressure whereby the unvaporized oil is reduced in temperature, introducing fresh oil into the said last-named chamber and admixing it with the said unvaporized oil, intimately contacting the unvaporized oil and fresh oil mixture with the said vapors in said chamber whereby the mixture is distilled, separately collecting the remaining unvaporized portion of said unvaporized oil and fresh oil mixture, separately withdrawing the vapors from said chamber including vapors of said fresh oil, partially condensing said vapors and passing at least a portion of the resulting condensate to said confined passageway to constitute the charging stock therefor.

12. The method of converting relatively high boiling hydrocarbon oils into lower boiling products which comprises heating a condensate stock formed in the operation to a conversion temperature while maintaining it under a substantial superatmospheric pressure and separating it into a vaporized portion and an unvaporized portion while under superatmospheric pressure, separately reducing the pressure upon said vaporized and unvaporized portions, admixing the said resulting unvaporized portions with fresh oil and contacting the mixture with said vaporized portions in countercurrent flow whereby the said mixture is heated and constituents thereof are vaporized, separately collecting the remaining unvaporized portion of said mixture, separately withdrawing the vapors and subjecting them to a condensation operation, and passing at least a portion of the resulting condensate to said conversion stage to constitute the aforesaid charging stock therefor.

13. The method of converting relatively high boiling hydrocarbon oils into lower boiling products which comprises heating a condensate stock formed in the operation to a conversion operation while maintaining it under a substantial superatmospheric pressure and separating it into a vaporized portion and an unvaporized portion while under superatmospheric pressure, separately reducing the pressure upon said vaporized and unvaporized portions, whereby the latter are reduced to a temperature below that of the vapors, admixing the said resulting unvaporized portions with fresh oil and contacting the mixture with said vaporized portion in countercurrent flow whereby the said mixture is heated and constituents thereof are vaporized, separately collecting the remaining unvaporized portion of said mixture, separately withdrawing the vapors and subjecting them to a partial condensation oper-

ation and passing at least a portion of the resulting condensate to said conversion stage to constitute the aforesaid charging stock therefor.

14. The method of converting relatively high boiling hydrocarbon oils into lower boiling products which comprises flowing a stream of condensate stock formed in the operation through a confined passageway while heating the latter to bring the oil stream to a conversion temperature and maintaining thereon a superatmospheric pressure, reducing the pressure on the heated oil and discharging it into an enlarged chamber maintained under a materially reduced superatmospheric pressure to secure a desired vaporization therein while maintaining a conversion temperature in said chamber, separately removing vapors and unvaporized oil from said chamber and discharging said products into another chamber maintained under a materially reduced pressure whereby the unvaporized oil is reduced in temperature, introducing fresh oil into the said last-named chamber and admixing it with the said unvaporized oil, intimately contacting the unvaporized oil and fresh oil mixture with the said vapors in said chamber whereby the mixture is distilled, separately collecting the remaining unvaporized portion of said unvaporized oil and fresh oil mixture, separately withdrawing the vapors from said chamber, including vapors of said fresh oil, partially condensing said vapors and passing at least a portion of the resulting condensate to said confined passageway to constitute the aforesaid charging stock therefor.

15. In processes for treating high boiling point hydrocarbons to produce low boiling point products therefrom, in which the high boiling point hydrocarbons are subjected to pressure distillation in a pressure distillation zone, the vapors and unvaporized residue separately removed from the pressure distillation zone, the vapors subjected to fractionation to condense therefrom products heavier than the desired product, the unvaporized residue delivered to a zone of reduced pressure wherein evaporation of constituents thereof is effected by the contained heat of the residue, the improvement which comprises utilizing charging oil as a cooling medium for fractionating vapors removed from the zone of pressure distillation and thereafter introducing the charging oil, prior to any cracking treatment thereof, to the unvaporized residue being delivered to the zone of reduced pressure.

16. In processes for treating high boiling point hydrocarbons to produce low boiling point products therefrom, in which the high boiling point hydrocarbons are subjected to pressure distillation in a pressure distillation zone, the vapors and unvaporized residue separately removed from the pressure distillation zone, the vapors subjected to fractionation to condense therefrom products heavier than the desired product, the unvaporized residue delivered to a zone of reduced pressure wherein evaporation of constituents thereof is effected by the contained heat of the residue, the improvement which comprises preheating charging oil for the process by heat extracted from vapors removed from the zone of pressure distillation, then introducing the charging oil, prior to any cracking treatment thereof, to the zone of reduced pressure in which distillation of unvaporized residue removed from the zone of pressure distillation is effected to volatilize from the charging oil constituents amenable to treatment in the zone of pressure distillation, subjecting the thus volatilized con-

stituents of the charging oil to fractionation and returning the condensate derived to the zone of pressure distillation.

17. A hydrocarbon oil cracking process which comprises passing the oil in a restricted stream through a heating zone and heating the same therein to cracking temperature under pressure, discharging the heated oil into a vapor separating zone and separating the same therein under pressure into vapors and unvaporized oil, separately removing the vapors and unvaporized oil from said separating zone, passing charging oil for the process in indirect heat exchange with hot products formed in the operation, combining charging oil so preheated with said unvaporized oil, partially distilling the resultant mixture under lower pressure than is maintained on said separating zone thereby vaporizing portions of the charging oil and said unvaporized oil, condensing heavier fractions of the vapors thus evolved, and supplying the condensed heavier fractions to said heating zone.

18. A hydrocarbon oil cracking process which comprises passing the oil in a restricted stream through a heating zone and heating the same therein to cracking temperature under pressure, discharging the heated oil into a vapor separating zone and separating the same therein under pressure into vapors and unvaporized oil, separately removing the vapors and unvaporized oil from said separating zone, dephlegmating said vapors in heat exchange with charging oil for the process and thereby preheating the charging oil, combining the preheated charging oil prior to any cracking treatment thereof with said unvaporized oil, partially distilling the resultant mixture under lower pressure than is maintained on said separating zone thereby vaporizing portions of the charging oil and said unvaporized oil, condensing heavier fractions of the vapors thus evolved, and supplying the condensed heavier fractions to said heating zone.

19. In processes for treating high boiling point hydrocarbons to produce low boiling point products therefrom, in which the high boiling point hydrocarbons are subjected to pressure distillation in a pressure distillation zone, the vapors and unvaporized residue separately removed from the pressure distillation zone, the vapors subjected to fractionation to condense therefrom products heavier than the desired product, the unvaporized residue delivered to a zone of reduced pressure wherein evaporation of constituents thereof is effected by the contained heat of the residue, the improvement which comprises utilizing charging oil as a cooling medium for fractionating vapors removed from the zone of pressure distillation and thereafter introducing charging oil, prior to any cracking treatment thereof, to the unvaporized residue being delivered to the zone of reduced pressure.

20. In processes for treating high boiling point hydrocarbons to produce low boiling point products therefrom, in which the high boiling point hydrocarbons are subjected to pressure distillation in a pressure distillation zone, the vapors and unvaporized residue separately removed from the pressure distillation zone, the vapors subjected to fractionation to condense therefrom products heavier than the desired product, the unvaporized residue delivered to a zone of reduced pressure wherein evaporation of constituents thereof is effected by the contained heat of the residue, the improvement which comprises preheating charging oil for the process by heat extracted from vapors removed from the zone of pressure distillation, then introducing the charging oil, prior to any cracking treatment thereof, to the zone of reduced pressure in which distillation of unvaporized residue removed from the zone of pressure distillation is effected to volatilize from the charging oil constituents amenable to treatment in the zone of pressure distillation, subjecting the thus volatilized con-

process by heat extracted from vapors removed from the zone of pressure distillation, then introducing charging oil, prior to any cracking treatment thereof, to the zone of reduced pressure in which distillation of unvaporized residue removed from the zone of pressure distillation is effected to volatilize from the charging oil constituents amenable to treatment in the zone of pressure distillation, subjecting the thus volatilized constituents of the charging oil to fractionation and returning the condensate derived to the zone of pressure distillation.

21. A hydrocarbon oil cracking process which comprises passing the oil in a restricted stream through a heating zone and heating the same therein to cracking temperature under pressure, discharging the heated oil into a vapor separating zone and separating the same therein under pressure into vapors and unvaporized oil, separately removing the vapors and unvaporized oil from said separating zone, dephlegmating said vapors in heat exchange with charging oil for the process and thereby preheating the charging oil, combining preheated charging oil prior to any cracking treatment thereof with said unvaporized oil, partially distilling the resultant mixture under lower pressure than is maintained on said separating zone thereby vaporizing portions of the charging oil and said unvaporized oil, condensing heavier fractions of the vapors thus evolved, and supplying the condensed heavier fractions to said heating zone.

22. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with hot vapors flashed and separated from said withdrawn oils to form a composite distillate, fractionally condensing and separating out heavier fractions from said composite distillate to form a composite condensate, and introducing said composite condensate into the mass of hydrocarbon oils subjected to said cracking temperature and pressure heretofore mentioned.

23. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, and introducing said composite condensate into the mass of hydrocarbon oils subjected

to said cracking temperature and pressure heretofore mentioned.

24. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils, vapors so distilled and separated with hot vapors flashed and separated from said withdrawn oils to form a composite distillate, fractionally condensing and separating out heavier fractions from said composite distillate to form a composite condensate, introducing said composite condensate into said reflux condensate portion to form a mixture of oils, and introducing the mixture of oils thus formed into the mass of hydrocarbon oils subjected to said cracking temperature and pressure heretofore mentioned.

25. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, introducing said composite condensate into said reflux condensate portion to form a mixture of oils, and introducing the mixture of oils thus formed into the mass of hydrocarbon oils subjected to said cracking temperature and pressure heretofore mentioned.

26. The method of cracking hydrocarbon oils which comprises subjecting a flowing stream of distillate oil cracking stock to cracking under high superatmospheric pressure, discharging the stream of cracked products into an enlarged separating zone maintained under superatmospheric pressure wherein vapors and liquid residual products separate, separately withdrawing the resulting vapors, fractionating them to condense as reflux condensate heavier constituents thereof, separately withdrawing liquid residual products from said separating zone and discharging them into a distilling zone maintained under a materially reduced pressure wherein further vaporization of said residual products is effected, passing relatively cool charging oil in indirect heat exchange with hot cracked products formed in the operation to heat said charging oil to a temperature sufficient to vaporize lower boiling components

thereof, separating the vaporized constituents of said charging oil, thereafter introducing the pre-heated unvaporized fresh oil into said low pressure distilling zone at a point above the point of introduction of said residual products thereinto whereby said preheated fresh oil undergoes distillation in intimate contact with vapors evolved from said residual products, fractionating the resulting mixture of vapors from said low pressure distilling zone in admixture with vaporized constituents separated from said charging oil to form a clean condensate stock, subjecting a flowing stream of condensate formed during said last-named fractionation to cracking under high superatmospheric pressure and discharging the resulting cracked products into said enlarged separating chamber.

27. The process of treating hydrocarbon oil which comprises passing relatively clean cracking stock through a cracking zone wherein it is raised to a cracking temperature and subjected to conversion, introducing the resulting cracked products into a distilling zone wherein lighter products separate as vapors from the heavier liquid residues, passing fresh relatively heavy charging stock in indirect heat exchange relation with light products so separated whereby said charging stock is heated to a distilling temperature, introducing the preheated charging stock into a stripping zone wherein lighter constituents thereof separate as vapors leaving liquid reduced crude, passing resulting reduced crude in indirect heat exchange with heavier liquid products separated in the distilling zone and introducing the further heated reduced crude into said distilling zone in countercurrent flow with the vapors rising therethrough, fractionating the vapors from said distilling zone, condensing and collecting the uncondensed vapors resulting from said last-named fractionation and withdrawing unvaporized residual products from said distilling zone.

28. The process in accordance with claim 27 which further comprises passing reflux condensate formed in the fractionating zone to the cracking zone as clean relatively heavy cracking stock therefor.

29. The process in accordance with claim 27 which further comprises removing the light vapors from said stripping zone and introducing said vapors into the fractionating zone for fractionation therein.

30. In the process for producing lower boiling hydrocarbon products from higher boiling hydrocarbons wherein the higher boiling hydrocarbons are subjected to conversion conditions and the conversion products separated into vapors and unvaporized residuum; the improvement which comprises introducing vapors formed during the conversion treatment into a distilling zone, introducing unvaporized residuum from the conversion treatment into said zone above the introduction of said vapors and at a temperature below that of said vapors, introducing charging oil for the process into said zone above the introduction of unvaporized residuum whereby the hot vapors flow countercurrent to the unvaporized residuum and the fresh charging oil, fractionating the vapors from said distilling zone, collecting and removing a clean condensate resulting from said fractionation, subjecting said condensate to conversion treatment, withdrawing residuum from said distilling zone, preheating said fresh charging oil by indirect heat exchange with said last-named residuum and con-

densing and collecting uncondensed vapors from said fractionation as a final distillate product.

31. The process of treating hydrocarbon oil which comprises passing relatively clean cracking stock through a cracking zone wherein it is raised to a cracking temperature and subjected to conversion, introducing all of the resulting cracked products into a distilling zone wherein lighter products separate as vapors from the heavier liquid residuum, passing fresh relatively heavy charging stock in indirect heat exchange relation with light products so separated whereby said charging stock is heated to a distilling temperature, introducing the preheated charging stock into a stripping zone wherein lighter constituents thereof separate as vapors leaving liquid reduced crude, passing the reduced crude into said distilling zone in countercurrent flow with vapors rising therethrough, combining vapors from said stripping zone with the vapors from said distilling zone, fractionating the combined vapors to condense heavier constituents thereof, condensing and collecting uncondensed vapors from said last-named fractionation as the desired distillate product and withdrawing unvaporized residual products from said distilling zone.

32. In a process for converting higher boiling hydrocarbons into lower boiling hydrocarbons suitable for motor fuel wherein a relatively clean cracking stock is passed through a cracking zone and subjected to conversion therein, the resulting converted products then introduced into a separating zone for separating lighter vapor products from heavier liquid residuum; the improvement which comprises passing the liquid residuum into a zone maintained at a pressure below that existing in said separating zone to effect further vaporization of said liquid residuum by the contained heat thereof, passing fresh charging oil in direct countercurrent contact with vapor products from said separating zone to vaporize lighter constituents thereof, commingling the vapors resulting from distillation of said fresh oil and the vapors from the distillation of the liquid residuum, fractionating the commingled vapors to form a condensate, condensing and collecting the uncondensed vapors resulting from the last-named fractionation to form the desired distillate product and subjecting condensate formed during said fractionation to conversion treatment in said first-named cracking zone.

33. In the process for producing lower boiling hydrocarbon products from higher boiling hydrocarbon products wherein the higher boiling hydrocarbons are subjected to conversion conditions, the conversion products separated into vapors and unvaporized residuum, the vapors subjected to fractionation and the uncondensed vapors from said fractionation condensed and collected as a final distillate product; the improvement which comprises passing the unvaporized residuum into a vertically elongated distilling chamber provided with a plurality of vertically spaced baffles and maintained under reduced pressure wherein further vaporization is effected by the contained heat of the residuum, passing charging oil in indirect heat exchange with hot products formed in the operation, passing charging oil so preheated into the reduced pressure distilling chamber above the introduction of said unvaporized residuum and above the lowermost baffle therein whereby said charging oil flows countercurrent to the upflow of

- vapors therein and serves as a refluxing medium for the vapors liberated from said residuum in the reduced pressure chamber and whereby the lighter components of the charging stock are
- 5 vaporized, fractionating the vapors from the reduced pressure zone to form a condensate and subjecting condensate formed during said fractionation to the first-mentioned conversion treatment.
- 10 34. A process for converting hydrocarbon oil which comprises subjecting oil to cracking conditions in a heating zone, passing the products from the heating zone into an enlarged chamber wherein the products separate into vapors and
- 15 unvaporized residue, withdrawing residue from the enlarged chamber and subjecting it to distillation in a zone of reduced pressure with the formation of further vapors and residue, condensing heavier constituents of the first and last
- 20 named vapors, separating a portion of condensate so formed containing constituents of said last named vapors and commingling the same without prior heating to cracking temperature with heated oil from the heating zone prior to its entrance into the enlarged chamber to cool said heated oil.
- 25 35. In the hydrocarbon oil cracking process wherein the oil is heated to cracking temperature under pressure while passing in a restricted stream through a heating zone, the heated oil thence discharged into a reaction zone, from which vapors and unvaporized oil are separately withdrawn, and the unvaporized oil flash-distilled by pressure reduction with the formation of
- 30 flashed vapors; the improvement which comprises fractionating the flashed vapors thereby forming a reflux condensate, introducing at least a portion of the refluxed condensate, without prior heating to cracking temperature into the
- 35 heated oil discharging from the heating zone to thereby cool said heated oil, fractionating the vapors removed from the reaction zone and returning a portion of the reflux condensate separated therefrom to the heating zone for further
- 40 treatment therein.
- 45 36. A process for the production of gasoline and other oils from hydrocarbon oils which comprises subjecting a stream of hydrocarbon oil to cracking temperature under pressure to crack
- 50 said oil, passing the stream of cracked products into an enlarged separating zone wherein vapors and residual liquid products separate, withdrawing residual oils from said separating zone and passing them to a distilling zone maintained under reduced pressure to flash a portion thereof
- 5 into vapors, separately withdrawing vapors from said reduced pressure distilling zone, heating and distilling additional hydrocarbon oils in a separate distilling zone to effect a distillation of vapors therefrom, separately withdrawing vapors from said separate distilling zone, mixing vapors withdrawn from said distilling zones, fractionally condensing and separating out heavier fractions from the resulting vapor mixture to form a condensate, withdrawing condensate from said fractionating operation and supplying said condensate, in the absence of residual constituents of the oils treated in said separate distilling zones to the aforesaid cracking operation as said stream of hydrocarbon oil.
- 20 37. A process for the production of gasoline and other oils from hydrocarbon oils which comprises subjecting a stream of hydrocarbon oil to cracking temperature under pressure to crack said oil, passing the stream of cracked products
- 25 into an enlarged separating zone wherein vapors and residual liquid products separate, separating said vapors into a vapor portion containing gasoline fractions and a reflux condensate portion, withdrawing residual oils from said separating zone and passing them to a distilling zone maintained under reduced pressure to flash a portion thereof
- 30 into vapors, separately withdrawing vapors from said reduced pressure distilling zone, heating and distilling additional hydrocarbon oils
- 35 in a separate distilling zone to effect a distillation of vapors therefrom, separately withdrawing vapors from said separate distilling zone, mixing vapors withdrawn from said distilling zones, fractionally condensing and separating out heavier fractions from the resulting vapor mixture to form a condensate, withdrawing condensate from said fractionating operation and supplying said condensate, in the absence of residual constituents of the oils treated in said separate distilling zones, together with said reflux condensate separated from the vapors from said enlarged separating zones to the aforesaid cracking operation as said stream of hydrocarbon oil.

ROBERT E. WILSON. 50

CERTIFICATE OF CORRECTION.

tent No. 2,021,471.

November 19, 1935.

ROBERT E. WILSON.

It is hereby certified that error appears in the printed specification of the above numbered patent requiring correction as follows: Page 2, second column, line 32, after the syllable "ample" insert a comma; page 3, first column, line 5, after the numeral "11" second occurrence, insert a comma; and second column, line 6, for "500°F." read 550°F.; and that the said Letters Patent should be read with these corrections therein that the same may conform to the record of the case in the Patent Office.

Signed and sealed this 21st day of January, A. D. 1936.

Leslie Frazer
